United States Patent Office.

DANIEL WARNER, OF BOSTON, MASSACHUSETTS, ASSIGNOR TO HIMSELF, JAMES T. BOWMAN, RICHARD C. DOUGHERTY, AND DANIEL J. HUCKINS.

Letters Patent No. 80,577, dated August 4, 1868.

IMPROVEMENT IN LAMP-WICK TRIMMERS.

The Schedule referred to in these Letters Patent and making part of the same.

TO ALL PERSONS TO WHOM THESE PRESENTS MAY COME:

Be it known that I, DANIEL WARNER, of Boston, in the county of Suffolk, and State of Massachusetts, have invented a new and useful Clamp-Gauge or Device to be Used for Facilitating the Trimming of the Wick of a Lamp; and I do hereby declare the same to be fully described in the following specification, and represented in the accompanying drawings, of which—

Figure 1 is a side elevation,

Figure 2 an edge elevation,

Figure 3 a top view,

Figure 4 a bottom view, and

Figure 5 a transverse and vertical section of it.

It consists of a flat tube, A, slit down through, and at its opposite edges, for some distance from its top, as shown at *a*, and having applied to each of the branches or parts *b b*, on opposite sides of the slits *a a*, a flange or guard, *c*, to extend from the upper end of each branch, in manner as represented in the drawings. The upper portions *b b* constitute elastic or spring-jaws.

In order to use the article for the purpose for which it is intended, it is to be slipped on the wick-tube of the lamp whose wick may require trimming, the said wick-tube being introduced into the lower end of the article, and caused to extend up into it a short distance. Next, the wick, by means of its elevator, is to be raised within the clamp-gauge, and so as to project a short distance above its top, after which it may be trimmed to the form of such top by a pair of scissors. The object of the flanges of the top is to prevent the scissors from cutting into the top of the tube. While cutting off the wick, such wick should be held firmly in place by pinching the gauge, so as to contract its jaws upon the wick.

By means of such device, a wick of a common flat-wick kerosene-burner may be trimmed with great ease and regularity.

I claim the clamp-gauge, as constructed of the flat tube slit at its opposite edges, as set forth.

I also claim the combination and arrangement of either or both the flanges *c c*, with the flat tube slit at its opposite edges as specified, the whole being for the purpose or purposes as explained.

DANIEL WARNER.
